UNITED STATES PATENT OFFICE

WILLIAM C. CARTER, OF FLINT, MICHIGAN

SOLENOID MOTOR FOR FUEL PUMPS

Original application filed September 28, 1925, Serial No. 59,149. Divided and this application filed November 14, 1928. Serial No. 319,241.

The main object of my present invention is to provide a solenoid motor for fuel pumps, that is equipped with an automatically-operating, intermittent switch whose contacts are held pressed tightly together during one stroke of the pumping element by a means separate and distinct from the magnetic attraction of the solenoid, and are separated with a quick break by a spring-actuated hammer in which energy is stored by the magnetic attraction of the solenoid during the said stroke of the pumping element.

The figure of the drawing is a vertical longitudinal sectional view illustrating my improved motor and controlling switch combined with a liquid fuel pump whose pumping element consists of a flexible diaphragm.

Referring to the drawing, A designates the diaphragm of the pump, which is preferably composed of a plurality of layers α of fabric treated to render it impervious to water, gasoline and the like, without making it brittle or inflexible. Said diaphragm is arranged in opposed relation to a rigid, cup-shaped member 1, so as to form a pumping chamber 2, and the peripheral edge portion of said diaphragm is combined with the member 1 and an opposed clamping member 3 that tightly clamps or grips the edge of the diaphragm.

When the pump is in operation the diaphragm A moves towards and away from the wall 1 of the pumping chamber, so as to draw liquid fuel into said pumping chamber from a source of supply, and thereafter force said fuel out of said chamber to an internal combustion engine or to a carburetor associated with such an engine. The pumping chamber 2 is connected by one or more ports 4 with a valve passageway 5 equipped with an inlet valve 6 and a discharge valve 7. When the pump is in operation liquid fuel is drawn from a source of supply through a conduit that is connected to an inlet 8 at the lower end of the valve passageway 5 and is discharged through an outlet 8^a at the upper end of the said passageway.

The diaphragm A is fixed in one direction by a solenoid which comprises a coil B and a core composed of a movable core piece C and a stationary core piece C', the movable core

piece C being connected to the central portion of the diaphragm A in any suitable manner, as, for example, by means of a screw or bolt 10, screwed into the core piece C and arranged with its head in engagement with a clamping plate 11 that clamps the central portion of the diaphragm A against the core piece C. As the diaphragm is formed from fabric, there is some slack in same between the clamping plate 11 at the center of the diaphragm and the clamping member 3 that grips the peripheral edge of the diaphragm. In order to take up this slack and keep the diaphragm taut, a spring 9 is arranged in engagement with the diaphragm at a point between the peripheral edge portion of the diaphragm and the central portion of the diaphragm that is clamped to the movable core piece C, said spring 9 exerting a counteracting force on the diaphragm. Due to the fact that the movable member C of the core is directly connected to the diaphragm A, the spring 9 constantly exerts pressure on the core piece C in a direction tending to move it away from the stationary core piece C', and as said spring 9 surrounds the core piece C and is interposed between the diaphragm A and the opposed member 3 which forms an abutment for one end of the spring 9, it effectively prevents the diaphragm from flopping back and forth in opposite directions to the pumping strokes, thereby preventing the diaphragm from making an objectionable noise when the pump is in operation and adding materially to the life of the diaphragm.

The coil B of the solenoid is arranged inside of a housing of magnetic material formed by the member 3 previously referred to and by a substantially cup-shaped member 12 that is combined with the member 3, as illustrated in the drawing. The spool on which the coil B of the solenoid is wound preferably comprises a tubular portion 13 of non-magnetic material and a tubular portion 13^a of magnetic material that is connected to the housing member 3 and which is of sufficient area to insure the flux passing freely from the flux field to the core when the solenoid circuit is closed, thereby making it possible to operate the pump with a relatively small

amount of electric current. Both members 5 C and C' of the core are formed of magnetic material and the stationary member C' has a cone-shaped portion that telescopes in a tapered socket in the inner end portion of the movable member C of the core. A hammer D, which is also formed of magnetic material, is reciprocatingly mounted in the stationary member C' of the core at the center of said member, which hammer will be 10 hereinafter more fully described.

The electric circuit that is used to energize the solenoid of the pump is provided with two switches, one a manually-operated switch (not shown) that is closed when the 15 pump is in use, and the other an automatically-operating, intermittent switch that opens and closes the solenoid circuit intermittently so as to cause the movable core piece 20 C to reciprocate, and thus actuate the diaphragm or pumping element A of the pump. Said intermittent switch may be of any preferred construction, but I prefer to equip the pump with a switch whose movable 25 contact consists of a revolvably mounted member of disk or annular form arranged so that it will move into and out of engagement with two stationary contacts, one of which is electrically connected with the coil of the 30 solenoid and the other being grounded. Said intermittent switch is arranged inside of a removable cap piece 12^a on the end wall of the housing of the solenoid and comprises a 35 revolvble member 14 of disk or annular form that constitutes the movable contact of the switch and two stationary contacts 15 and 15^a arranged in spaced relation at one side of the movable contact 14, one of said stationary contacts being electrically connected to the 40 coil B of the solenoid and the other stationary contact being grounded. The movable contact 14 is carried by an insulator or contact carrier 16 that is rotatably mounted on a tubular member 17 which constitutes a 45 housing for a spring 18 that holds the contacts of the intermittent switch closed when the solenoid is imparting a suction stroke to the diaphragm. Said insulator 16 is moved outwardly or away from the stationary contacts 15 and 15^a by means of a tubular striking portion 19 on the hammer D which surrounds the spring housing 17, and said insulator is moved inwardly toward said stationary contacts by means of a stop 20 on a 50 rod 21 that is rigidly connected with the bolt or screw 10 in the movable core piece C. The contact carrier or insulator 16 of the intermittent switch is capable of bodily movement relatively to the hammer D and said hammer 55 D is so constructed and arranged that it will impart a sharp blow to the insulator 16 in a direction to open the solenoid circuit with a quick break at the end of the suction stroke of the diaphragm A. In the pump herein 60 illustrated the hammer D is provided with a

center socket that houses a spring 22 that is stronger than the spring 18, said spring 22 surrounding the rod 21 previously referred to. A washer 23 is mounted on said rod between one end of the spring 22 and a spring 24 that is stronger than the spring 22 and which is arranged so that it bears against the screw or bolt 10 in the movable core piece C, the spring 22 being confined between the washer 23 and the inner end of the socket in the hammer D that receives said spring. The striking portion 19 of the hammer surrounds the spring housing 17, and the inner end of said spring housing is arranged in opposed relation to a shoulder 25 on the hammer. The hammer D is arranged to reciprocate freely inside of the stationary member C' of the core and is provided with a radially-projecting flange 26 that is positioned between two stationary stops 27 and 28 of 75 cork or other relatively soft material that cooperate with said flange to limit the movement of said hammer in opposite directions.

When the solenoid circuit is open the movable member C of the core is held spaced away from the stationary member C' by the expansive force of the spring 9 and the movable contact 14 of the intermittent switch is held in engagement with the stationary contacts 15 and 15^a by the pressure which the stop 20 on the rod 21 exerts on the spring housing 17 whose flange 17^a bears against the insulator 16 that carries said movable contact 14. When the manually-operable switch of the solenoid circuit is closed, the movable 90 member C of the core moves inwardly towards the stationary core member C' and the hammer D which is free to reciprocate relatively to the stationary core member C' assumes the position shown in the drawing.

The inward movement of the core member C, namely, movement to the right, looking at the drawing, imparts a suction stroke to the diaphragm A and also builds up energy in the spring 22 of the hammer D and in the 100 stiff spring 24 that is arranged on the other side of the washer 23, it being understood that the hammer D is held at rest during the inward stroke of the core member C by the magnetic attraction of the solenoid. During 105 this time, namely, when the solenoid is imparting a suction stroke to the diaphragm, the contacts of the intermittent switch are held tightly together by the force of the spring 18 which is under compression at this 110 time. The spring 18 expands when the stop on the rod 21 moves to the right, and thus exerts pressure on the spring housing 17 in a direction to hold the flange 17^a thereon in engagement with the insulator 16. At the time 115 the core member C starts to move inwardly, namely, to the right from the position shown in the drawing, the space between the tapered surface on the core member C and the inclined surface on the inner end of the ham- 120

mer D is less than the space between the tapered surface on the core member C and the tapered surface on the core member C'. The inward movement of the core member C reduces the width of said spaces, and when the core member C reaches such a position that the washer 23 bears against the inner end of the hammer D, part of the flux path becomes short-circuited across the air gap or space between the tapered surface of the core member C and the inclined surface on the inner end of the hammer, due, of course, to the fact that said space or air gap is of less width than the space or air gap between the tapered surface on the core member C and the tapered surface of the core member C'. Consequently, the hammer D starts to move with the core member C, thereby causing the pulling force of the solenoid to be reduced automatically to such an extent that the solenoid exerts practically the same pull on the diaphragm at the end of the suction stroke as it exerted on the diaphragm at the beginning of the suction stroke. In other words, by forming the hammer D in such a manner that the inner end of same is separated from the tapered surface of the core member C by an air gap of less width than the air gap between the tapered surfaces of the core members C and C', I prevent the pull of the solenoid on the diaphragm from building up progressively as the core member C moves inwardly. This is highly desirable, as it prevents the diaphragm from being operated at such a high speed that time enough is not provided to insure a full charge of fuel entering the pumping chamber before the diaphragm starts to move in the opposite direction, namely, to the left, under the influence of the spring 9. At the time the hammer starts to move with the core member C, the spring 24 and spring 22 are exerting a longitudinal thrust on the hammer D that is only slightly less than the force which holds the core member C and hammer D together. Further inward movement of the core member C reduces the air gap between the members C and C', thereby cutting down the attraction power of the hammer D to such an extent that the spring 24 breaks it loose from the core member C, and the hammer D thereafter moves outwardly under the influence of the spring 22, the shoulder 25 on said hammer engaging the inner end of the spring housing and moving said housing longitudinally in a direction to relieve the pressure on the insulator 16 which carries the movable contact 14 of the intermittent switch. Thereafter, the striking portion 19 of said hammer imparts a sudden blow to the insulator 16 and moves it outwardly away from the stationary contact of the intermittent switch, thus causing the solenoid circuit to be opened with a quick break. Immediately thereafter the core piece C moves outwardly, or to the left back to the

position shown in the drawing, under the influence of the spring 9 whose tension was increased by the inward movement of said core piece, and during this outward stroke of the core piece C the stop 20 on the rod 21 first compresses the spring 18 into the spring housing 17, and then engages the flange 17^a on the spring housing and moves said housing in a direction to compress the spring 22, thus causing the contact 14 to move into engagement with the contacts 15 and 15^a, as shown in the drawing, and close the solenoid circuit. 70 75

Having thus described my invention, what I claim as new and desire to secure by Letters Patent is:

1. In a motor, a solenoid having a movable core, an intermittently operating switch for governing the energizing circuit of said solenoid, a spring for holding the contacts of said switch closed during the stroke of the core of the solenoid in one direction, and a separate means of greater force for holding said contacts open during the stroke of the core of the solenoid in the opposite direction. 80 85

2. In a motor, a solenoid, a switch for governing the energizing circuit of the solenoid, comprising a contact carrier, a hammer combined with the solenoid, said hammer being capable of bodily movement relatively to said contact carrier, means whereby the magnetic attraction of the solenoid will hold the hammer in spaced relationship with said contact carrier during part of the stroke of the core of the solenoid in one direction, and means for overcoming the magnetic attraction of the solenoid on the hammer and for causing said hammer to strike the contact carrier and separate the contacts of said switch with a quick break. 90 95 100

3. In a motor, a solenoid, a switch for governing the energizing circuit of the solenoid, a hammer combined with the solenoid in such a way that the magnetic attraction of the solenoid holds the hammer at rest during part of the actuating stroke of the core of the solenoid and is reduced near the end of the stroke, a spring for overcoming the magnetic attraction exerted by the solenoid on the hammer, an independent spring for causing said hammer to separate the contacts of said switch with a quick break, and a third spring of less strength than the springs previously referred to arranged so as to hold the contacts of said switch closed during the actuating stroke of the solenoid core. 105 110 115

4. In a motor, a solenoid provided with a core composed of a stationary member and a movable member that are normally separated by an air gap, a switch for governing the energized circuit of the solenoid, a spring arranged so that it is normally active for holding the contacts of said switch closed, a movable hammer of magnetic material arranged so that it remains at rest during the first portion of the actuating stroke of the 120 125 130

movable core member, and a resilient actuating means for causing said hammer to separate the contacts of said switch with a quick break, arranged so that energy will be stored in same by the actuating stroke of the movable core member.

5. In a motor, a solenoid provided with a core composed of a stationary member and a movable member, a switch for governing the energizing circuit of the solenoid, a hammer for separating the contacts of said switch with a quick break, constructed of magnetic material and arranged to reciprocate inside of the stationary member of the core of the solenoid, two springs of different tension arranged between said hammer and the movable member of the core and adapted to be compressed by the actuating stroke of said member, a spring combined with said switch for normally holding the contacts of same closed, and a means connected with the movable member of the core and arranged to move with same for varying the tension of said switch spring.
- 10 6. In a motor, a solenoid, a switch for controlling the energizing circuit of the solenoid, a reciprocating hammer for separating the contacts of said switch with a quick break, arranged so that it is held at rest by the magnetic attraction of the solenoid during a portion of the actuating stroke of the solenoid core, a resilient actuating means for said spring in which energy is stored during the actuating stroke of said core, stops that 15 co-operate with a part on said hammer to limit the movement of same, and a resilient means whose tension varies according to the position of the movable member of the core, for normally holding the contacts of said switch closed.

WILLIAM C. CARTER.
